Attorneys

UNITED STATES PATENT OFFICE.

ANDREW C. FOWLS, OF NEW PHILADELPHIA, OHIO.

TRAFFIC SIGNAL OR INDICATOR.

Application filed March 27, 1920. Serial No. 369,262.

To all whom it may concern:

Be it known that I, ANDREW C. FOWLS, citizen of the United States, residing at New Philadelphia, in the county of Tuscarawas and State of Ohio, have invented certain new and useful Improvements in Traffic Signals or Indicators, of which the following is a specification, reference being had to the accompanying drawings.

10 This invention relates to an improved traffic signal or direction indicator for use in connection with automobiles and the like and an object of the invention is to provide a device of this character particularly adapted for position on the side of the automobile in a suitable location adjacent the driving side and so as to not interfere with the opening and closing of the door, particularly when used on closed automobiles and designed to be manipulated so as to indicate the intention of the chauffeur to make a turn.

Another object is to provide a suitable housing for the traffic signal or indicator 25 preferably carried by the side of the wind shield and means rotated on the interior of the body of the automobile for operating the signal or indicator.

Still another object embodies a traffic signal or indicator comprising a tubular arm 30 consisting of two united sections, whereby an electric bulb may be secured in the hand section which is provided with an opening covered with suitable transparent material, whereby the light from the bulb may be 35 readily seen, in combination with a circuit for lighting the bulb.

A further object involves improved means 40 for actuating the traffic signal or direction indicator, preferably carried by the steering column of the steering wheel and having a wire or cable connection with the indicator for moving it to a laterally extended position.

45 A still further object is the provision of an actuator wherein a lever is employed for riding over a quadrant and having contact means to cooperate with stationary contacts for closing an electric circuit for lighting the bulb and being means to limit the lever in its movement from one portion of the quadrant to the other, and means for preventing lifting the lever too much when moving the same.

55 While the design and construction at present illustrated and set forth is deemed pref-

erable, it is obvious that as a result of a reduction of the invention to a more practical form for commercial purposes, the invention may be susceptible to changes, and the right to these changes is claimed, provided they are comprehended within the scope of what is claimed.

The invention comprises further features and combination of parts, as will be herein-after set forth, shown in the drawings and claimed.

In the drawings:

Figure 1 is a view of a portion of a body of an automobile showing the traffic signal or indicator as applied to the side of the wind shield and the actuator as carried by the steering column.

Figure 2 is a vertical sectional view through the housing or casing showing the traffic signal or indicator in its normal position in full lines, and extended laterally in dotted lines.

Figure 3 is a plan view of the actuator as carried by the steering column and showing the actuating lever for the indicator.

Figure 4 is a sectional view through the contacts of the segment and the operating lever, and showing the diagrammatic arrangement of the wiring for the lamp in the indicator hand.

Figure 5 is a sectional view on line 5—5 of Figure 2.

Figure 6 is a sectional view on line 6—6 of Figure 2.

Figure 7 is an enlarged detail sectional view of a portion of the hand of the indicator arm, showing the lamp therein and illustrating how the lamp and hand are connected to the arm.

Referring more especially to the drawings, 1 designates a housing, which is provided with elongated loops or members 2 to engage over suitable hooks 3 which are carried by the side of the automobile preferably on the side of the wind shield, so as to support the housing or casing in position. It is obvious that the housing or casing may be located on any other part of the body, suitable to permit the signal or indicator to be seen, particularly from the rear of the automobile.

The housing or casing is preferably rectangular in formation and has one longitudinal edge portion open as shown to permit the indicator or signal 4 to be displayed. The indicator or signal (which is in the

2

form of a tubular arm) comprises a body section 5 and a hand section 6, wherein an electric light bulb 8 is located. The body section 5 adjacent where it connects to the hand section is provided with a transverse wall 5^a, from which a tubular extension 5^c extends. This tubular extension constitutes a lamp socket, in the bottom of which a contact 5^d is mounted. One side of the lead 14 connects with the contact 5^d, while the other side of the lead 14 is grounded at 14^a to the body section. The plug (which is provided with an annular flange or collar 9) of the electric light bulb engages in the socket and connects with the contact 5^d. The plug of the bulb is in turn grounded to the wall of the socket in the usual manner, so as to complete the circuit through the bulb. In order to assemble the bulb and the hand section, the plug of the bulb is first inserted in the socket, the collar or flange 9 resting upon the margin of the tubular extension 5^c (which constitutes the socket) after which the hand section 6 telescopes the bulb, so that its threaded extension 7 will connect with the threaded interior of the wall of the body section 5. In other words the extension 7 of the hand section engages between the outer wall of the body section and the tubular extension 5^c. The hand section when so connected acts to hold the bulb in position, by means of an internal flange 6^a, which bears upon the collar or flange 9 and holds it against the margin of the tubular extension 5^c. The hand section has opposite openings 10 in its opposite side walls, which are closed by glass or other transparent material 11 so that the light from the bulb can be readily seen from the front or from the rear. The body section of the arm indicator or signal is movable with a tubular pivot 12 which is mounted in bearings in the front and rear walls of the housing or casing. This tubular pivot comprises the opposite sections which are connected to the opposite sides of the indicator or signal arm. One of the sections of the tubular pivot is provided with an opening 13 through which the usual electrical conductors 14 pass so as to connect with the bulb in the hand section.

The pivoted end of the body section of the direction indicator or arm 4 has integral therewith a projection or lug 15, which extends from the body section at an angle such as will permit the arm or indicator to be moved on its pivot to a lateral position with relation to the housing or casing. In order to move the arm to such a position, a wire or cable 16 is connected to the lug or projection and is in turn connected at 17 to a short arm 18 of a lever 19 which is pivoted at 20 on a quadrant and by moving the lever over the quadrant and by moving action may be imparted to the wire or cable

16 in order to tilt or move the indicator arm or signal to a lateral position, which will indicate the intention of the chauffeur to turn the automobile.

The quadrant 21 carrying the arm 19 is mounted or connected to the steering column at 22 below the steering wheel by means of a suitable clamp 23. The quadrant has an arcuate portion over which the lever 19 moves, there being shoulders 24 and 25 adjacent the opposite ends of the arcuate portion so as to limit the lever in its movement. When the lever is in contact with the shoulder 25, the circuit is open, but when the lever is moved, as shown in dotted lines to engage the shoulder 24, the circuit is closed, as there are contacts 28, carried by the lever engaging contacts 27 of the arcuate portion of the quadrant. One of the leads or conductors 14 of the bulb is connected to any suitable source of electrical energy such as a battery, while the other lead or conductor 14 is connected to one of the contacts 27. The other contact 27 is in turn connected to the battery or other source of electrical energy.

The lever 19 is provided with contacts 28, which are carried by a conductor plate 29. This conductor plate is insulated from the lever 19 by means of the block of insulation 19^a. The contacts 27 are insulated from the arcuate portion of the quadrant by means of the insulation 30^a. It will be noted that when the lever 19 is moved from its normal position to its operative circuit closing position, the contacts 28 will engage the contacts 27 and close the circuit, thereby lighting the bulb. At the same time the contacts 28 cooperate with the contacts 27 and the circuit is closed, the lever moves the signal or indicator to a lateral position extending from the housing or casing. A guide 30 is carried by the arcuate portion of the quadrant and extends over the lever 19, thereby guiding the lever and preventing the lever from being raised too high from the arcuate curved portion.

It is the aim to employ the light carried by the hand section of the indicator at night only and in such an instance, the switch 31 carried by the lead or conductor 32 from the contact 27 to the battery may be opened, thereby preventing the circuit from being closed when the lever is moved to an operative position.

The invention having been set forth, what is claimed as new and useful is:

1. In a socket for a signal arm for a traffic signal, having means for actuating the arm, said arm comprising a body section provided at one end with internal threads and a transverse disc wall at the base of the threads, a tubular lamp socket projecting from said wall and spaced from the internal threaded surface of the end of the body sec-

tion, an electric light bulb having its plug end provided with an annular collar to engage the margin of the wall of said socket when the plug end of the bulb engages 5 within said socket, a hand section having an extension connected with the internal threaded surface of the end of the body section and fitting around the wall of the socket, said hand section having an internal 10 flange bearing upon the collar of the plug and holding it upon the wall of the socket, and electrical means for lighting the bulb when the arm is actuated.

2. A lamp socket comprising in combination with a signal arm for a traffic signal having means for actuating the arm, said signal arm comprising a body section provided with internal threads at one end and a transverse disc wall at the base of said

threads, a lamp socket projecting axially 20 from the wall and spaced from the internal threaded surface of the end of the body section, a lamp including a plug engaging said socket, said plug having an annular collar engaging the margin of the wall of 25 the socket, a hand section provided with an axial extension engaging the internal threads of the end of the body section and fitting around the wall of said socket, said hand section having an internal shoulder 30 bearing upon the collar of the plug to retain the lamp rigidly in position, and electrical means for lighting the bulb when the arm is actuated.

In testimony whereof I hereunto affix my 35 signature.

ANDREW C. FOWLS.
